PROCESS FOR THE PRODUCTION OF LOW-BOILING DIOLEFINS

Filed June 1, 1943

UNITED STATES PATENT OFFICE

2,376,061

PROCESS FOR THE PRODUCTION OF
LOW-BOILING DIOLEFINSJean Paul Jones, Bartlesville, Okla., assignor to
Phillips Petroleum Company, a corporation of
Delaware

Application June 1, 1943, Serial No. 489,289

8 Claims. (Cl. 260—680)

This invention relates to the production of di-olefin hydrocarbons from paraffin hydrocarbons by dehydrogenation. It relates more particularly to the production of such diolefins by means of catalytic dehydrogenation wherein unreacted hydrocarbons comprising paraffins and olefins are recycled to a dehydrogenation step. The invention has particular reference to the production of diolefins such as butadiene, pentadiene and isoprene from the corresponding paraffin hydrocarbons, preferably by means of catalytic dehydrogenation. This application is a continuation-in-part of my copending application, Serial No. 404,420, filed July 28, 1941.

It has been proposed to produce diolefins by dehydrogenation in a single step wherein a paraffin hydrocarbon such as normal butane is charged to the dehydrogenation step, a diolefin such as butadiene is recovered from the dehydrogenation effluent, and a hydrocarbon fraction containing unreacted hydrocarbons, such as normal butane and butenes, are separated from the effluent and returned to the dehydrogenation step. It has also been proposed to produce diolefins from paraffin hydrocarbons by the use of at least two dehydrogenation steps in the first of which paraffins are dehydrogenated to olefins and in the second of which olefins are dehydrogenated to diolefins. In such a process there is generally a recycle of unreacted hydrocarbons to one or more of the dehydrogenation steps. In preparing the charge to such dehydrogenation processes it is impossible from a practical point of view to separate a hydrocarbon material such as normal butane in a state of high purity, and in most instances when the particular desired hydrocarbon is present in a concentration of about 95 per cent or more, it is considered to be in a sufficiently high state of purity for practical operations. At times the concentration may even be somewhat lower than 95 per cent although generally it will not be appreciably lower than about 90 per cent. Also in such dehydrogenations there is a tendency for isomeric forms of the hydrocarbons being treated to be formed as by-products in the dehydrogenation step. Thus, in the dehydrogenation of normal butane and/or normal butenes to form butadiene, there is a tendency for small amounts of isobutene and isobutane to be formed. When a hydrocarbon fraction containing unreacted hydrocarbons is recycled to the dehydrogenation step, it will contain such isomeric hydrocarbons in either case, and as a result after a steady state of operation has been reached, the total charge to a dehydrogenation step will

contain a substantial amount of such isomeric hydrocarbons, which do not contribute directly to the production of the desired diolefins, which not only decrease capacity of the dehydrogenation units but also tend to enter into undesired side reactions.

As discussed in my copending application, I have found that this tendency for isomeric hydrocarbons to build up in such a dehydrogenation system may be effectively kept under control and limited to any desired extent by removing a portion of the recycled hydrocarbon fraction, separating such isomeric hydrocarbons from this removed portion of the hydrocarbon fraction and returning unseparated hydrocarbons to the dehydrogenation system. In the process of the present invention this is accomplished by subjecting undesired isomeric hydrocarbons in the portion so removed to isomerization whereby these undesired hydrocarbons are converted to a desired isomeric form, and returning resultant desired hydrocarbons to the dehydrogenation system. This procedure may be followed either when the undesired isomeric hydrocarbons are present as a result of formation within the dehydrogenation system or when they are present as a result of being included as impurities as a charge to the dehydrogenation system or for any other reason.

30 An object of my invention is to produce di-olefin hydrocarbons.

It is an object of my invention to produce low-boiling diolefin hydrocarbons from paraffin hydrocarbons of the same number of carbon atoms per molecule.

35 It is a further object of my invention to produce diolefin hydrocarbons by means of catalytic dehydrogenation of more saturated hydrocarbons under conditions such that there is a minimum formation of undesired by-products.

40 Further objects and advantages of this invention will become apparent from the accompanying disclosure and discussion.

45 My invention will now be described in connection with the accompanying drawing which shows diagrammatically by way of a flow sheet a preferred arrangement of apparatus for practicing my invention together with certain modifications thereof. The description of my invention in connection with the drawing will also serve to exemplify the same.

50 Referring now to the drawing, a suitable hydrocarbon material enters the system through a pipe 10 controlled by a valve 11 and is passed to a separating means illustrated by the fractionating

column 12. Preferably such a hydrocarbon mixture will comprise predominantly hydrocarbons of a single number of carbon atoms per molecule such as a butane fraction comprising both normal butane and isobutane, or a pentane fraction comprising both normal pentane and isopentane. For purposes of illustration it will be considered that the material charged through pipe 10 will be a butane fraction. The fractionating column 12 is so operated as to separate a normal butane fraction and an isobutane fraction from other hydrocarbons contained in the material charged. The isobutane fraction is removed from the system through pipe 13, low-boiling material may be discharged through valve 14. Any undesired high-boiling material is discharged through a pipe 18 controlled by a valve 20. A normal butane fraction of as high a purity as is practical, and preferably containing normal butane as at least 95 per cent of the mixture, is removed through a pipe 16 controlled by a valve 18 and may be passed through a valve 17 directly to a single dehydrogenation unit 18. The dehydrogenation unit 18 is comprised of suitable heating units or furnaces, catalyst chambers, and the like, known to the art for effecting and maintaining catalytic non-destructive dehydrogenation of low-boiling hydrocarbons. The catalyst chambers may be so arranged that heat is supplied to the catalyst body or bodies and to the reacting mixture. When a single dehydrogenation unit is used, the dehydrogenation is conducted to effect a dehydrogenation both of paraffins and olefins to form olefins and diolefins, respectively, along with free hydrogen. The resulting products pass through a pipe 20 controlled by a valve 21 to separating means 22. Separating means 22 will include suitable fractionating columns, condensing units, heat exchangers, solvent extraction units and the like suitable for effecting a separation of the material charged into the desired fractions as will be discussed. A diolefin fraction, in this case containing a high concentration of butadiene, is recovered as a product of the process from separating means 22 through a pipe 23 controlled by a valve 24. A fraction containing light gases with a high concentration of free hydrogen formed by the dehydrogenation is removed from separating means 22 through a pipe 25 and may be discharged at least in part from the system through a valve 26. Any undesired heavy material may be discharged from the system through a pipe 27 controlled by a valve 28. Light hydrocarbons such as C₂ and C₃ hydrocarbons and any methane not passed through pipe 25 may be discharged through pipe 24. A recycle fraction, which in this case will comprise predominantly normal butane and normal butenes, is removed from separating means 22 through a pipe 30 and a substantial portion thereof, preferably a predominant portion, is passed through valve 31 to be returned to the dehydrogenation unit 18. As discussed, this recycle fraction will contain appreciable amounts of isomeric hydrocarbons, in this case isobutane and isobutene. In accordance with this modification of the invention, a portion of the recycle material passing through pipe 30 is passed therefrom through a pipe 32 and is passed through valve 33 to a hydrogenation unit 34. Any undesired portion of this stream may be discharged from the system through pipe 35 controlled by a valve 36. Hydrogen in an amount sufficient to effect a substantially complete saturation of unsaturated material charged to hydrogenation unit 34 is added to the system through a pipe 37. This

hydrogen may be added entirely or in part through a valve 38, but generally there will be more than sufficient hydrogen in the stream discharged through pipe 25 to suffice for this operation, and any desired portion of this stream may be passed from pipe 25 through a pipe 40 controlled by a valve 41 to pipe 37 and hydrogenation unit 34.

In some instances it may be found more desirable to operate separating means 22 so as to separate a fraction containing isobutane and isobutene in higher concentration than would otherwise be present in the recycle stream passing through valve 31 back to the hydrogenation system. Such a fraction can be separated by carefully controlled fractional distillation, preferably aided by an azeotrope-forming agent such as sulfur dioxide, and can then be passed to hydrogenation unit 34, and a recycle stream with a depleted amount of isobutane and isobutene, or substantially free of these hydrocarbons, is passed to the dehydrogenation system as by being removed from separating means 22 through pipe 29 and valve 40.

The hydrogenation in unit 34 will be one of simple, nondestructive, substantially complete saturation of unsaturated hydrocarbons charged thereto and may be carried out in the presence of an active hydrogenation catalyst, such as finely divided nickel on an inert support such as pumice, silica gel, or the like, under a suitable pressure and temperature. Such temperature and pressure will generally not need to be greatly elevated and conditions for any particular stock being treated may be readily determined by trial by one skilled in the art. The effluent of the hydrogenation is passed from unit 34 through a pipe 42 controlled by a valve 43 to a separating means 44. Any undesired low-boiling material such as unreacted free hydrogen and hydrocarbons of a fewer number of carbon atoms than the material treated in the dehydrogenation unit 18 may be discharged from the system through a pipe 45 controlled by a valve 46. A paraffin hydrocarbon fraction preferably predominantly of a single number of carbon atoms per molecule, in this case a butane fraction, is recovered through a pipe 47 and may be passed through valve 48 directly to pipe 10 and fractionating unit 12.

An isobutane fraction separated from column 12 is passed from pipe 13 through pipe 70 and valve 71 to isomerization unit 72 wherein it is contacted with a suitable isomerization catalyst under conditions such as to convert isobutane into normal butane with a minimum of formation of hydrocarbons of lower and higher molecular weight. A preferred catalyst for such an operation is aluminum chloride or bromide associated with the corresponding hydrogen halide. The aluminum chloride, or bromide, may be used in a free state or as a supported catalyst as is well known in the art, and as may be found most suitable for any particular operation. A somewhat elevated reaction temperature, such as in the range of about 200 to 400° F., will favor the production of normal butane and will permit operation with a short reaction time. However, such elevated temperatures are also conducive to the formation of undesired by-products, and it will be necessary to limit the reaction time and also the extent of the conversion so that such side reactions do not take place to an extensive extent. Isomerization unit 72 will also include suitable apparatus for removing hydrocarbon constituents from isomerization effluents, and a hydrocarbon stream con-

taining a substantial proportion of desired normal butane is removed through pipe 73 and returned to fractionating column 12 through valve 74. If the concentration of normal butane is sufficiently high that this material can be subjected directly to dehydrogenation, it may be passed from pipe 73 through pipe 75 and valves 76 and 77 to pipe 15 for dehydrogenation.

In case the butane fraction passing through pipe 17 contains a sufficiently high concentration of isobutane, it may be passed directly to isomerization unit 72 through pipe 80 controlled by valve 81, but this will usually not be a suitable method of operation unless an iso-C₄ concentrate is charged to hydrogenation unit 34. Isobutane may be passed to the system as a charge stock for producing butadiene through pipe 80 controlled by valve 82 and through pipes 88 and 70 to isomerization unit 72.

Substantially the same procedure may be followed when converting normal pentane to piperylene with substantially the same treatments of normal C₅ and iso C₅ hydrocarbons for the treatment discussed for normal C₄ and iso C₄ hydrocarbons respectively. When converting isopentane to isoprene a similar procedure will be followed, but with conversion of the isoparaffin to the diolefin and with isomerization of the normal paraffin to the isoparaffin. Thus isopentane will be separated as an overhead product of column 12 through a pipe 80 controlled by valve 84 and will be passed through pipe 75 and valve 77 to the later portion of pipe 15 and to the dehydrogenation system while normal pentane will be passed from a low point of column 12 through pipe 82 controlled by valve 83 to isomerization unit 72.

In some instances it may be desired to conduct the dehydrogenation operation in two or more steps; in such an event the stream passing through pipe 15 will be passed therefrom through pipe 59 controlled by a valve 51 to a dehydrogenation unit 52 which as in the case of dehydrogenation unit 18 is comprised of suitable heating units or furnaces, catalyst chambers and the like known to the art for effecting and maintaining catalytic nondestructive dehydrogenation of low-boiling hydrocarbons. The material charged to dehydrogenation unit 52 should be predominantly paraffinic, and the dehydrogenation conditions should be such that there is an optimum formation of mono-olefins of the same number of carbon atoms per molecule as the paraffins charged. The dehydrogenation effluent is passed through the pipe 58 controlled by valve 54 to separating means 55. A fraction containing the desired olefins, produced by the dehydrogenation is removed from separating means 55 through a pipe 66 controlled by a valve 57 and is passed back to pipe 15 for introduction to dehydrogenation unit 18. With such an operation valve 17 in pipe 15 will be closed. Undesired low-boiling materials, including free hydrogen produced by the dehydrogenation, may be discharged from the system through pipe 68 controlled by a valve 69 passing from separating means 55. Free hydrogen contained in this stream may be used in the hydrogenation unit 34, and if such use is desired the hydrogen may be introduced through valve 38 as will be readily appreciated. In some instances the material passing through pipe 68 will contain substantially all of the unreacted paraffin charged to dehydrogenation unit 52, in which case separating means 55 can be operated simply to separate a hydrocarbon fraction such as a butane-butene fraction from lower boiling material.

However, in some instances it may be found desirable to have a high concentration of olefins in the material charged to dehydrogenation unit 18. In such a case separating means 55 will also include suitable equipment for separating olefins from paraffins, such as selective solvent extraction equipment as will be readily appreciated by those skilled in the art. Paraffin hydrocarbons separated in such a manner may be returned to dehydrogenation unit 52 as through pipe 60 controlled by a valve 61. In some instances with either modification of the dehydrogenation system, material charged through pipe 60 may contain substantially only hydrocarbons of a single carbon atom skeleton structure and may in such a case constitute the sole charge to the process. When a fraction containing a high proportion of olefins suitable for dehydrogenation into diolefins is available from any outside source such a material may be charged to the system through pipe 60 when dehydrogenation unit 18 is the only part of the dehydrogenation system. When such a charge is available and a dehydrogenation system includes both units 52 and 18, such an olefin-containing charge may be introduced to the process through pipe 62 controlled by a valve 63 passing into pipes 30 and 15 directly to dehydrogenation unit 18, and in some instances material charged through pipe 62 may constitute the sole charge to the process.

It has previously been mentioned that the dehydrogenation carried out in units 18 and/or 52 will be conducted under conditions known to the art and will generally be conducted under a relatively low pressure with or without the presence of diluent material such as hydrocarbons inert under the dehydrogenation conditions, nitrogen, steam, carbon dioxide and the like. Sometimes introduction of small amounts of free hydrogen along with the charge to a catalyst bed has a beneficial effect, especially upon the initial portion of a catalyst bed before hydrogen is produced by dehydrogenation, and the presence of such added hydrogen does not retard unduly or upset the dehydrogenation reaction. Such introduction can be made for example, through pipe 60 and/or pipe 62. Any of various dehydrogenation catalysts may be used, among which the more preferred are alumina and/or chromium oxide catalysts such as bauxite treated with other materials such as an alkali or alkaline earth oxide, as barium oxide, unglowed chromium oxide, alone or in admixture with other oxides, and prepared from a gelatinous chromium hydroxide, from carefully controlled, low temperature decomposition of an ammonium chromate, and the like. Suitable dehydrogenation temperatures will generally be found in the range of 800 to 1300° F. A single stage dehydrogenation, as first described in connection with dehydrogenation unit 18, is preferably carried out with a catalyst comprising chromium oxide, or chromium oxide and alumina, at a temperature in the range of 950 to 1100° F. while a two-stage operation may be carried out with a similar catalyst under slightly less drastic time-temperature conditions in dehydrogenation unit 52, with subsequent dehydrogenation of resultant olefins at a higher temperature, such as within the range of 1050 to 1250° F., using a catalyst such as bauxite treated with barium hydroxide, or temperature-stabilized chromium oxide, with or without the presence of steam, or the like, as diluent. In all such dehydrogenation steps low pressures, which may be subatmospheric but which generally will

be slightly above atmospheric, are preferred. The above conditions are particularly suitable for treating C₄ hydrocarbons; the treatments of C₅ hydrocarbons are substantially within the same ranges, with slightly lower temperatures in otherwise comparable cases.

The amount of the paraffin-olefin mixture which, in any particular case, is removed and passed to the hydrogenation unit 34 will depend on the degree of purity of the stock charged to the dehydrogenation unit or units, and on the isomerizing characteristics of the dehydrogenation conditions. With less pure stock and/or appreciable tendencies to form isomeric hydrocarbons, a larger portion will need to be passed to the hydrogenation step than with more favorable conditions. Generally the amount so treated will be at least about 5 per cent of the total recycle stream, and while it may be as high as about 25 per cent, it will generally be more economical to modify other conditions to obtain more favorable operation than to operate so that more than about 15 per cent is so treated. Suitable ratios in any particular case can be readily determined by one skilled in the art. If large proportion of undesired isomeric hydrocarbons are present in the stream passing through pipe 26, it will be desirable to concentrate these, as previously discussed.

Pumps or compressors for the various streams in connection with the drawing have not been shown; general flow of the various streams, however, has been indicated and discussed, and suitable mechanical equipment for desired treatment of this material can be readily supplied, as required in any particular modification of my invention, by one skilled in the art. Similarly other units of equipment have been shown only diagrammatically but their functions have been described and explained so as to serve as suitable guides for adaption of suitable specific equipment for specific installations. It will be obvious to those skilled in the art that various modifications of my invention may be practiced as being included in the spirit of the disclosure and in the scope of the claims. In the present specification and claims when it is stated that a portion of a stream is removed therefrom, the term "portion" shall be understood to mean an unfractionated part which has the same composition as the stream from which it is removed.

My invention is particularly suited to the production of diolefins such as butadiene, pentadiene, and isoprene from the corresponding paraffin hydrocarbons. When a pentane fraction is charged to the system, the products may be fractionated into a normal butane fraction which may be treated under conditions optimum for the production of the corresponding diolefin. In such a case the products of hydrogenation of the fractions removed from the recycle stream may be charged to fractionating unit 12 as will be readily appreciated, and the normal butane dehydrogenated in separate equipment.

I claim:

1. A process for the production of butadiene, which comprises passing a normal butane fraction to a dehydrogenation zone and effecting a dehydrogenation thereof forming butadiene, separating from an effluent of said dehydrogenation a butadiene fraction as a product of the process, separating further a normal C₄ fraction substantially free from butadiene, comprising predominantly normal butane and normal butenes and containing a minor amount of iso-C₄

hydrocarbons, passing a portion of said normal C₄ fraction to said dehydrogenation, subjecting a further portion of said normal C₄ fraction to non-destructive hydrogenation in the presence of free hydrogen to form a paraffinic fraction containing normal butane and isobutane, passing said paraffinic fraction to fractionating means, removing from said fractionating means an isobutane fraction, subjecting said isobutane to isomerization to form normal butane, and passing normal butane so formed to said dehydrogenation to form additional butadiene.

2. A process for the production of butadiene, which comprises passing a butane-containing mixture to a fractionating means, separating therefrom a normal butane fraction, passing said normal butane fraction to a dehydrogenation zone and effecting a dehydrogenation thereof forming butadiene, separating from an effluent of said dehydrogenation a butadiene fraction as a product of the process, separating also a fraction containing free hydrogen, and separating further a normal C₄ fraction substantially free from butadiene, comprising predominantly normal butane and normal butenes and containing a minor amount of iso-C₄ hydrocarbons, passing a portion of said normal C₄ fraction to said dehydrogenation, subjecting a further portion of said normal C₄ fraction to nondestructive hydrogenation in the presence of free hydrogen from said fraction containing free hydrogen to form a paraffinic fraction containing normal butane and isobutane, passing said paraffinic fraction to said fractionating means, removing from said fractionating means an isobutane fraction, subjecting said isobutane to isomerization to form normal butane, and passing normal butane so formed to said dehydrogenation to form additional butadiene.

3. A process for the production of butadiene, which comprises passing a butane-containing mixture to a fractionating means, separating therefrom a normal butane fraction, passing said normal butane fraction to a dehydrogenation zone and effecting a dehydrogenation thereof forming butadiene, separating from an effluent of said dehydrogenation a butadiene fraction as a product of the process, separating also a fraction containing free hydrogen, and separating further a normal C₄ fraction substantially free from butadiene, comprising predominantly normal butane and normal butenes and containing a minor amount of iso-C₄ hydrocarbons, passing a portion of said normal C₄ fraction to said dehydrogenation, subjecting a further portion of said normal C₄ fraction to nondestructive hydrogenation in the presence of free hydrogen from said fraction containing free hydrogen to form a paraffinic fraction containing normal butane and isobutane, passing said paraffinic fraction to said fractionating means, removing from said fractionating means an isobutane fraction, subjecting said isobutane to isomerization to form a hydrocarbon fraction containing normal butane, and passing said hydrocarbon fraction to said fractionating means.

4. A process for the production of butadiene, which comprises passing a normal butane fraction to a dehydrogenation zone and effecting a dehydrogenation thereof forming butadiene, separating from an effluent of said dehydrogenation a butadiene fraction as a product of the process, separating further a normal C₄ fraction substantially free from butadiene, and separating also a fraction containing isobutane and isobu-

tene, passing said normal C₄ fraction to said dehydrogenation, subjecting said fraction containing isobutane and isobutene to nondestructive hydrogenation in the presence of free hydrogen to form isobutane, subjecting said isobutane to isomerization to form normal butane, and passing normal butane so formed to said dehydrogenation to form additional butadiene.

5. A process for the production of a desired low-boiling diolefin of at least four carbon atoms per molecule, which comprises passing a paraffin hydrocarbon having the same number of carbon atoms per molecule and same carbon atom skeleton structure as said desired diolefin to a dehydrogenation zone and effecting a dehydrogenation thereof forming the corresponding diolefin, separating from an effluent of said dehydrogenation a diolefin fraction as a product of the process, separating further from said effluent an aliphatic hydrocarbon fraction containing essentially hydrocarbons of the same number of carbon atoms per molecule and same carbon atom skeleton structure as said paraffin and desired diolefin and substantially free from diolefin and passing same to said dehydrogenation, separating also from said effluent an olefin-containing aliphatic hydrocarbon fraction containing hydrocarbons of a carbon skeleton structure isomeric to said paraffin and desired diolefin, subjecting said olefin-containing fraction to nondestructive hydrogenation in the presence of free hydrogen to form a paraffinic hydrocarbon fraction, subjecting a paraffin hydrocarbon from said paraffinic fraction and isomeric in structure to the first said paraffin and desired diolefin to isomerization to form an isomeric paraffin corresponding to the first said paraffin and desired diolefin, and passing the last said paraffin to said dehydrogenation to form an additional amount of said diolefin.

6. A process for the production of butadiene, which comprises passing a butane-containing mixture to a fractionating means, separating therefrom a normal butane fraction, subjecting said normal butane fraction to dehydrogenation under dehydrogenation conditions suitable for effecting the production of butadiene, separating from an effluent of said dehydrogenation system a butadiene fraction as a product of the process, separating also from said effluent a normal C₄ fraction substantially free from butadiene, separating further from said effluent a fraction containing isobutane and isobutene, separating still further from said effluent a fraction containing free hydrogen, passing said normal C₄ fraction to said dehydrogenation, subjecting said fraction containing isobutane and isobutene to nondestructive hydrogenation in the presence of free hydrogen from said hydrogen-containing fraction under hydrogenation conditions suitable for forming a completely saturated paraffinic fraction containing isobutane, subjecting the butane fraction resulting from said hydrogenation to isomerization under isomerization conditions suitable for converting isobutane to normal butane, passing the butane fraction resulting from said isomerization to the aforesaid fractionating means, and removing from said fractionating means an isobutane fraction and passing same as an additional charge stock to said isomerization.

7. The process of claim 5 in which the first said paraffin hydrocarbon is normal pentane and pentadiene is produced as a product.

8. The process of claim 5 in which the first said paraffin hydrocarbon is isopentane and isoprene is produced as a product.

JEAN PAUL JONES.
